AXEL H. ANDERSSON, OF BENTON HARBOR, MICHIGAN, ASSIGNOR, BY MESNE ASSIGNMENTS, TO REMINGTON RAND INC., OF TONAWANDA, NEW YORK, A CORPORATION OF DELAWARE.

DRAWER SUPPORT.

Application filed February 7, 1924. Serial No. 691,127.

My invention relates to that class of supports for drawers largely used in sectional metal filing cases wherein the drawer is supported on roller-supported extension slides arranged to support the drawer while permitting its withdrawal to nearly the front line of the casing. The object of my invention is to provide an improved drawer support of this type which shall be compact and occupy a minimum of space, be strong, simple and durable in construction and efficient in operation, and which in general shall be desirable and notably well adapted to serve the purposes for which it was designed. With these objects and purposes in view I have devised and invented the improved drawer support hereinafter described in detail and illustrated in the accompanying drawing, the essential elements of my invention being more particularly pointed out in the appended claims.

In the drawing Figure 1 is a central longitudinal section of a sectional filing case unit to which my invention is shown applied, the drawer and parts beyond the plane of the section being shown in elevation; Fig. 2 is a perspective of the drawer support members alone; and Fig. 3 is a transverse section of the support through one pair of double rollers near the center of one of the pair of intermediate extension members of the same.

The same reference characters indicate the same parts in all the figures of the drawing. As in other devices of this character the support comprises two counterpart sets of three members each, one set at each side of the drawer. Each set includes a stationary track member secured to the inside face of the adjacent casing, a floating intermediate extension member, and a drawer member secured to the drawer and movable relatively to the floating member. In my improved support the stationary track member is in the form of a sheet-metal strip 1 formed with vertical outer portions 2-2^a separated by a central rib 3, and having upper and lower horizontal flanges, marked 4 and 5, respectively. The central ribs of the two track members affords spacing surfaces for guiding the adjacent faces of the floating members later to be described with minimum frictional contact, and the upper and lower flanges provide track surfaces for the roll-

ers of such members. The track members 55 are secured to the drawer casing in any suitable manner, as by spot welding.

The floating members, 6-6 are formed of strips of sheet-metal which in the present instance are inwardly flanged at the bottom 60 and connected to cross-strips 7-7. Near the front end of each member 6 upon its vertical or body portion is mounted a front lower roller 8 which extends through an opening cut in the bottom flange a sufficient distance 65 to ride upon the bottom flange 5 of the track member. Adjacent the center, each floating member is provided with an upper intermediate roller 9 arranged to cooperate with the upper flange 4 of the track member, and a lower intermediate roller 10 which extends through an opening cut in the bottom flange 60 of the floating member to permit it to cooperate with the lower flange 5 of the stationary track member. This lower intermediate 75 roller is loosely mounted to permit it to automatically adjust itself to slight variations in the faces of the track members and shift slightly without binding under the changing stresses to which it is subjected, as 80 the drawer is moved out and in. At the rear end of each floating member is arranged an upper rear roller 11 which is so positioned as to cooperate with the upper flange 4 of the track member. 85

The rails 12 which support the drawer are in the present instances strips of channel iron secured to the outer face of the drawer in any suitable manner, as by spot welding. The upper and lower flanges of the rails are arranged to pass between the pairs of rollers 9 and 10, the lower flanges resting upon the front rollers 8 and the upper flanges being arranged to cooperate with the upper rollers 11 in the operation of the drawer. 95

Suitably positioned stops are provided to limit the movements of the parts. To this end, the floating frame consisting of the members 6 and cross-bars 7 is provided with laterally extending blocks 6^a secured to the bottom of the opposite flanges of the members 6 and arranged to bring up at the limit of outward movement of the frame against lugs 1^a extending inwardly from the bottom flange 5 of the stationary track. The drawer 100 is provided with a buffer 7^b arranged in an open-front box 7^c which is secured to the under face of the bottom wall of the drawer, 105

this buffer being arranged to cooperate with a lip 7* struck up from the front cross bar 7 of the floating frame.

The top flange 4 of each track member may 5 be longitudinally slotted for a short distance at a point about midway of its length, to permit a loop 4* to be bent down below the level of the top of the associated floating member 6 for the purpose of preventing lateral disengagement of the parts under abnormal strains 10 to which the structure might occasionally be subjected in use.

Inasmuch as the mode of operation of the 15 parts is well known in the art it will suffice to explain that whether the center of gravity of the drawer is in front of or to the rear of the rollers 8 in the act of shifting the drawer in or out, the rails 12 will be forced to bear upon the loosely-pivoted rollers 10 and cause 20 them to roll upon the lower horizontal flanges of the stationary track members, thus causing the floating frame to move in the same direction as the drawer at one-half its speed in consequence of the action of the pivots 25 of the rollers in their bearings in the floating frame. My invention as before indicated, resides not in this known mode of operation broadly, but in the compact and efficient mechanical construction and arrangement and assemblage of the parts, associated 30 and related as described, through which the drawer is thus supported and guided.

I claim:

1. A drawer support comprising a pair 35 of stationary track members each having a vertical intermediate portion secured to the drawer casing and horizontal upper and lower flanges extending towards each other; a pair of floating members each having a vertical body portion arranged parallel and adjacent said stationary track members and a horizontal bottom flange extending to-

wards the center of the drawer below the plane of the drawer bottom and above said lower flange of the stationary track member 45 and having four rollers mounted on the inside face of said body portion, the said rollers including a front bottom roller above the plane of said first-mentioned horizontal lower flange and a pair of intermediate 50 rollers and an upper rear roller below the plane of said upper flange; said floating members being rigidly secured together by cross-bars secured to their horizontal bottom flanges; and a pair of rails secured to 55 the drawer and each arranged to pass below the said upper rollers and above said lower rollers of its corresponding floating member.

2. A drawer support comprising a pair 60 of stationary track members each having a vertical intermediate portion secured to the drawer casing and horizontal upper and lower flanges extending towards each other, a pair of floating members each having a 65 vertical body portion arranged parallel with and adjacent said stationary track member and having four rollers mounted on the inner side thereof, the said rollers including a front bottom roller above the plane of the 70 bottom flange and a pair of upper and lower intermediate rollers and an upper rear roller below the plane of said upper flange, the upper flanges of the track members being severally longitudinally slotted and the portion of each member adjacent its slit being bent down in a short loop below the level of the top of the associated floating member and a pair of rails secured to the drawer and severally arranged to pass below said upper 80 rollers and above said lower rollers of its corresponding floating member.

AXEL H. ANDERSSON.
